UNITED STATES PATENT OFFICE.

PETER R. HAMMES, OF KANSAS CITY, MISSOURI.

ROTARY DISPLAY STAND.

Application filed March 29, 1928. Serial No. 265,640.

This invention relates to improvements in display devices, and more particularly to a rotary display device for exhibiting a plurality of rolls or bolts of cloth.

5 Many types of exhibitors have heretofore been proposed, and likewise devices for holding bolts of cloth in an upright position for exhibition to a tentative customer.

10 According to the present invention, a rotary device of this type is provided which differs from preceding devices in its cheapness of construction and simplicity of arrangement, and in its steadiness and ease of use.

15 Another object of this invention is to provide a structure which may be constructed of light materials and in which the holding elements brace the supporting table top.

A further feature of the invention is the 20 provision of the holding devices so that they are practically self-supporting irrespective of the holding means, whereby they yield added strength to the holding means which locates them for easy traveling or rotation in front of 25 a customer.

With these and other objects in view, as will appear in the course of the following specification and claims, I have shown one 30 illustrative form of the invention on the accompanying drawings, in which:

Figure 1 is a plan view of the support with a number of bolt-goods holders thereon, with a part of the construction shown in section for greater clearness.

35 Fig. 2 is a vertical section substantially on line 2—2 of Fig. 1.

Fig. 3 is a perspective view of a portion of the support, showing the disposition of the bolt-goods holders thereon.

40 According to this invention, a bolt goods holder of peculiar shape, which resembles a Z in its horizontal projection, is mounted upon a support: the ends of the member or holder are usually secured to the support, while 45 the middle portion is bent upward into a vertical plane whereby to form a loop to enter a bolt of goods, so that the holder will support this bolt of goods in a vertical position for display. In particular, a number of these 50 bolt-goods holders are arranged on a rotative disk hereinafter called a "table top". This table top may be made of thin material and the several bolt-goods holders are secured thereto for substantially the length of their 55 end portions, whereby to stiffen and reinforce the table top. Furthermore, it is preferred

to have the respective vertical plane of the middle portion of each bolt-goods holder extend chordally of the rotatable table top, i. e., neither passing through the axis of rotation 60 nor being substantially tangent to the outer diameter of the table top, but located somewhere between these positions so that both an end and a part of a side of a bolt of goods is displayed.

65 In the accompanying drawings, a base member 10 is provided with feet 11 by which it is supported on a counter or the floor, etc., and with a central upstanding spindle member 12, as well as the shoulder 13 to support 70 a ball-bearing represented generally at 14.

A table top 15 has a central aperture fitting the spindle 12, and is preferably circular, polygonal, etc. in shape. It is represented in the present illustration as being flat on its top. 75 The engagement of the spindle 12 and of the ball bearing 14 stiffens this table top against rocking about a horizontal axis.

80 Mounted on this table top 15 are the bolt-goods holders 16, eight of these being employed in the illustration. As shown in Fig. 3, each of these members 16 has an end 17 which is straight and is mounted upon the table top 15, so that in conjunction with the similar ends of each of the other bolt holders 85 16 it forms a polygon, being a regular octagon in the illustration, on the upper side of the table top 15, thereby bracing and stiffening the table top when these members 17 are secured in position by the individual clips 18 90 thereof, which may be of metal or fibre material fixedly attached to the table top itself. The other end 17a of each of these bolt holders 16 is preferably bent at a slight angle with respect to the first member, and is likewise 95 straight and secured to the table top 15 by a similar clip 19. These inner ends are arranged likewise to form a polygon for stiffening and reinforcing the table top 15. It will be noted that any line, such as a—a in Fig. 1, 100 passed through the center of rotation of the spindle of the table 15 and the spindle 12 and through the extremity of one end of a bolt-holder, will pass substantially through the middle of the other end of the same or another holder, or in other words, the sides of the two polygons are staggered so that there is not a line of weakness extending diametrically across the table top.

105 It will be further noted that the rebent 110 formation of the middle portion is arranged for each bolt holder in a vertical plane, and

is illustrated as forming a substantially triangular loop which is adapted to pass into the center of a bolt of goods, whereby to hold the bolt in a vertical position. As shown in 5 Fig. 1, a bolt of goods B located on one of the bolt holders presents its outer edge for inspection and also a major portion of its side, without being obscured by overlapping of the next bolt BB. In this way, it is usually 10 unnecessary to remove a portion of the goods from the holder for first exhibition. The vertical plane through the middle portion of the bolt holder extends chordally with respect to the table top, i. e., it is neither diametrical thereof (whereby only the edge of a bolt would be exposed), nor tangential (whereby only the side of the bolt would be exposed).

Further, the rebent formation of the ends 20 of the bolt holder in the illustrated form is of advantage as preventing the withdrawal of the bolt holder without removal of one or more of the clamps 18, 19. In horizontal projection, the bolt holder is of Z shape, as 25 indicated in Fig. 1.

Although a specific employment of the invention has been described in this specification and illustrated in the drawing, it will be understood that the invention is not limited 30 thereto, but may be employed in many forms within the scope of the appended claims.

I claim:

1. In a display stand, a base, a table mounted on said base for rotation about a vertical 35 axis, and a plurality of bolt-goods holders mounted on the table top, each of said bolt-goods holders comprising a wire member having its ends parallel to the table top and being bent intermediate its ends in a vertical 40 plane to form a loop adapted to be received within a bolt of goods to support the same in a vertical position, and means to secure said ends to said table whereby to stiffen and reinforce the table.

2. In a display stand, a base, a table mounted on said base for rotation about a vertical 45

axis, and a plurality of bolt-goods holders mounted on the table top, each of said bolt-goods holders comprising a wire member having straight end portions and a looped middle 50 portion adapted to be received within a bolt of goods to support the same in a vertical position, said looped middle portion lying in a vertical plane intersecting said table at a chordal line with respect to the periphery 55 thereof so that an edge and substantially one side of a bolt of goods thereon is exposed for examination.

3. In a display stand, a thin table, and a plurality of bolt-goods holders mounted on the table top, each of said bolt-goods holders comprising a wire member having its ends arranged in contact with the table top and a looped middle portion adapted to be received 60 within a bolt of goods to support the same in a vertical position, said ends being arranged so that one respective end of each holder forms one side of respective polygons having their centers coincident, a line from such coincident centers passing through an angle of one polygon intersecting the side of the other polygon, whereby said polygons reinforce said table.

4. In a display stand, a base, a table mounted on said base for rotation about a vertical 75 axis, a plurality of bolt-goods holders, each of said bolt-goods holders comprising a wire member having its ends located in a plane and a looped middle portion adapted to be received within a bolt of goods to support 80 the same in a vertical position, said vertical plane intersecting said table top at a chordal line of said table, said member having a Z-shaped projection upon the table top, the respective inner and outer ends of all of said 85 members being arranged to form regular polygons with their centers at the axis of rotation, and means to hold said ends fixed to the table top whereby said ends constitute a reinforcement for said table.

In testimony whereof, I affix my signature.
PETER R. HAMMES.
